CLAIM

(7) The ornamental design for an electronic device having a display screen with graphical user interface as shown and described.

DESCRIPTION

FIG. 1 is a front elevation view of an electronic device having a display screen with graphical user interface showing the claimed design;

(Continued)

FIG. 2 is a rear elevation view thereof;
 FIG. 3 is a left side elevation view thereof;
 FIG. 4 is a right side elevation view thereof;
 FIG. 5 is a top plan view thereof;
 FIG. 6 is a bottom plan view thereof; and,
 FIG. 7 is an enlarged view of a portion of FIG. 1.
 The outer dashed broken lines in the figures show portions of an electronic device having a display screen, and form no part of the claimed design.
 The dot-dash broken lines in the figures show the outer boundary of the claimed design.
 The white areas within the boundary of the claimed design show portions of the electronic device having a display screen, the inner dashed broken lines within the white areas show portions of the electronic device having a display screen that form no part of the claimed design.
 The black area within the boundary of the claimed design shows a portion of a graphical user interface of the electronic device having a display screen. The white dashed broken lines within the black area show portions of the graphical user interface that form no part of the claimed design.
